COMBINED DIAL AND HANDS FOR A CLOCK OR SIMILAR ARTICLE

Loren K. Fargo, St. Paul, Minn.

Application November 28, 1949, Serial No. 6,295

Term of patent 14 years

(Cl. D42—10)

To all whom it may concern:

Be it known that I, Loren K. Fargo, a citizen of the United States, residing at St. Paul, county of Ramsey, and State of Minnesota, have invented a new, original, and ornamental Design for a Combined Dial and Hands for a Clock or Similar Article, of which the following is a specification, reference being had to the accompanying drawing, forming a part hereof.

Figure 1 is an elevation view of a combined dial and hands for a clock or similar article, showing my new design; and

Figure 2 is a top plan view of the same.

I claim:

The ornamental design for a combined dial and hands for a clock or similar article, as shown.

LOREN K. FARGO.
